UNITED STATES PATENT OFFICE.

MIRABEAU N. LYNN AND ELMORE P. LYNN, OF RISING SUN, INDIANA, AS-SIGNORS, BY MESNE ASSIGNMENTS, TO THE LYNN ENGINE COMPANY, OF DAYTON, OHIO.

DIRECT-ACTING STEAM-ENGINE.

SPECIFICATION forming part of Letters Patent No. 366,122, dated July 5, 1887.

Application filed January 16, 1886. Serial No. 188,722. (No model.)

To all whom it may concern:

Be it known that we, MIRABEAU N. LYNN and ELMORE P. LYNN, of Rising Sun, in the county of Ohio and State of Indiana, have invented certain new and useful Improvements in Direct-Acting Steam-Engines; and we do hereby declare the following to be a full, clear, and exact description of the same, reference being had to the accompanying drawings, forming a part of this specification, and to the figures and letters of reference marked thereon.

The present invention relates more especially to engines of the direct-acting type, wherein two or more pistons are caused to act successively upon a crank or equivalent device for converting reciprocating into rotary motion; and it consists, generally, in the novel and improved mechanism for effecting the admission to and escape of steam from the cylinders for connecting the pistons and crank for controlling the steam-supply, as well as in certain minor features of construction and arrangements of parts, as hereinafter fully described, and pointed out in the claims.

In the accompanying drawings, Figure 1 is a longitudinal vertical section, partly in elevation, and Fig. 2 an end view, partly in section, and with the head removed, of a double-cylinder engine, showing the application of our invention. Fig. 3 is an end view of the detachable head; Fig. 4, a sectional view of the piston and cylinder, taken on the line $x-x$ of Fig. 1, and with the cylinder-head removed. Fig. 5 is a diagrammatic view of a portion of the piston and cylinder, showing the relative positions of the inlet and exhaust ports at different points in the movement of the piston. Fig. 6 is an end view of a crank-shaft, pitmen, pistons, and connections, with frame and cylinders removed. Fig. 7 is a perspective view of the pitmen separated.

Similar letters of reference in the several figures denote the same parts.

In carrying into practice our present invention, and as auxiliary thereto, it is essential that we employ a main supporting-frame, a crank-shaft, B, two or more opposing cylinders, C, two pistons, D, and pitmen E, connecting each piston with the crank. Although

these parts are necessary, their form and construction may be varied at will, so long as the proper relation of the co-operating parts is preserved, as will presently be described; but we prefer the construction shown as embodying improved features which contribute materially to the success of the machine, considered as a whole.

As shown in the drawings, the main supporting-frame and cylinders C are united to form a casing for the reception of the operating mechanism and a support for the latter. This casing is composed, essentially, of the central cylindrical portion, A', open at one end and formed with diametrically-opposite cylinders C, the walls of the latter being made double, with an open space between for the circulation of steam, which is admitted at a to the jacket of the lower cylinder and passes through a channel, a' , to the jacket of the upper cylinder, from whence it escapes through a channel leading to an opening, a^2 , Fig. 2, in the end of the cylindrical portion A' of the casing.

To the open end of the casing A' is fitted and bolted a head, A², in which are formed three steam-passages, a^3 a^4 a^5 , communicating at one end with a central chamber, a^6 . The passages a^3 and a^4 communicate, respectively, with passages a^7 and a^8 in the main casing leading to the cylinders, while the passage a^5 communicates with the opening a^2 , from which the steam issues after circulating through the jackets of the cylinders, as described.

The driving-shaft B passes through and is supported within a bearing, a^9 , formed in the end A⁴ of the casing, and is provided with a crank-pin, B', and counterbalance-weight B², both of the latter being located and rotating within the cylindrical portion A' of the casing or frame A of the machine. This bearing a^9 is provided with conical apertures to receive the quarter-brasses a^{10} , within which the shaft rotates, said brasses receiving the thrust of the pistons, and, being made adjustable longitudinally of the shaft, they can be set up to compensate for wear. The brasses a^{10} are adjusted by bolts a^{11} , screwed into the end of the bearing and provided with shoulders a^{12} , press-

ing against the outer ends of said brasses, and the latter are withdrawn or held in position by bolts a^3 , passing through a ring or cap-plate, a^4 . The cap-plate a^4 fits over the shaft and is held in position by nuts a^5 , working on the bolts a^3 , and in a recess formed in the inner face of the cap-plate and surrounding the shaft is fitted a packing-ring, a^6 .

As it is our purpose in this engine to provide for the lubrication of the various operating parts by the steam and mingled water and oil contained within the casing, we form a channel, a^7 , at or near the inner end of the bearing and leading from a cup, a^8 , to the shaft for the admission of the lubricant, and connect the space between the cap-plate a^4 and bearing with the interior of the casing, as at a^9 , so as to balance the pressure of the steam in the bearing and permit the liquid to circulate therein by gravity, and we apply the packing-ring to the shaft in order to form a tight joint at the other end of the bearing, and thereby maintain this balancing of the pressure and at the same time prevent the escape of steam, &c., around the shaft.

The pitmen E are applied to the crank-pin and connected to their pistons in the following manner, to insure a constant bearing upon the crank-pin when operating to drive the latter and a bearing upon the opposite pitman when the cylinder is exhausting, and to permit of a rotary or oscillating movement of the pistons about their longitudinal centers: Each pitman is furnished with a transverse head or socket, c , formed at one end and on the side next the rod c' with a segmental flange, c^2 , and on the opposite end with an annular collar, c^3 , containing a segmental bearing, c^4 , for the crank-pin and an enlarged segmental bearing, c^5 , on the side opposite the rod c' , equal in depth but slightly exceeding in width the segmental flange c^2 . When applied to the crank-pin, the corresponding sides of the two pitmen are brought together, so that the segmental flange c^2 of the one will enter within the enlarged segmental bearing c^5 of the other and form a cylindrical bearing to receive the crank-pin. The flange c^2 being narrower than its bearing c^5 in the opposite collar, the two pitmen are free to vibrate independently upon the crank-pin, and at the same time are prevented from separating, and each pitman is given an extended bearing longitudinally of the crank-pin and upon the side to which the piston is applied. The pistons are united to the outer ends of the pitmen by ball-and-socket joints c^6 , which not only permit the pitmen to vibrate as the crank rotates, but furnish a bearing about which the piston-head can rotate or oscillate as it is reciprocating within the cylinder.

The pistons, which, like the pitmen, are duplicates, perform the double office of driving the crank and automatically controlling the opening and closing of the inlet and exhaust ports, as follows: The steam-passages a^7 and a^8 terminate within the cylinders in the ports

G G , preferably elongated in the direction of the length of the cylinders and formed with parallel edges g g . The pistons D are each formed with tubular extensions d , and the heads c^6 of the cylinders are depressed, so as to enter within the said extensions or prolongations d of the pistons. The tubular portion of the heads c^6 is slightly less in diameter than the interior of the tubular prolongations of the pistons, so as to leave sufficient space between them for the free circulation of steam. The packing-rings d^2 are applied to the exterior of and near the outer ends of the tubular extensions of the pistons, and the inlet-ports G are located within the cylinders in the plane of the revolution of the crank and at a point just beyond the traverse of the packing-rings d^2 toward the center. Within each cylinder, to one side of and below the inlet-ports, is located the exhaust-passage H , terminating within the casing A' . The pistons D are each provided with a channel or passage, I , communicating with the outer end of the cylinder. Each piston is furnished upon one side with a longitudinal extension, d^6 , which is cored or bored out on a line parallel with the axis of the cylinder to form a tubular socket, d^7 . These sockets d^7 , which stand opposite and facing each other, receive the cylindrical ends of a cross-head, J , which is loosely hung upon an extension, J' , of the crank-pin, by which means the pistons are simultaneously caused to oscillate from one side of the center to the other as they reciprocate to and fro in the cylinders.

The operation of the devices thus far described is as follows: Steam from the boiler enters at a , and after circulating through the steam-jackets of the cylinders is delivered into the chamber a^6 , from whence it passes to the inlet-port of each cylinder. Starting with the crank at one extreme of its throw and with the upper piston at the outer end of its stroke and the lower piston at the inner end of its stroke, as shown in Fig. 1, the port I in the face of the upper piston laps slightly the inlet-port G , forming an elongated opening through which the steam passes into the cylinder above the piston, while the port I in the lower piston in like manner uncovers one side of the exhaust-passage H . As the pistons descend the crank, rotating in the direction indicated by the arrow in Fig. 2, operates, through its extension J' and the cross-head J , to rotate both pistons in the direction indicated by the arrow, Fig. 2, thereby causing the port I of the upper piston to approach the port G in a diagonal direction to increase the area of the inlet, while the port I of the lower piston in like manner increases its exhaust-passage H . This lateral or oscillative motion of the piston, produced by the cross-head and crank, is greatest at the beginning of the stroke of the piston, and gradually diminishes as the crank approaches a horizontal line or quarter-revolution, when it almost entirely ceases, and as the crank passes said line the motion of the piston is reversed, causing the port I

in the upper piston to approach the exhaust-port and the port I in the lower piston to approach the inlet-port G, and, as the oscillation of the piston takes place simultaneously with 5 and is dependent upon its reciprocation, the port I will traverse an ellipse, as developed upon the interior of the cylinder, the extremes of the movement occurring at the middle of the stroke of the pistons in either direction 10 and while the crank is projected at right angles to the axes of the cylinders or line of movement of the pistons.

As will be obvious to the skilled mechanic, the point at which the inlet and exhaust 15 ports shall be opened widest or closed by the ports in the pistons depends upon the size, shape, and relative arrangement of the ports. In the example given the maximum opening occurs at about one-quarter stroke and the 20 inlet-ports are closed at five-eighths stroke, the opening of the inlet and exhaust ports taking place along the longer edges of the ports, and when the ports I in the piston stand nearly, if not quite, opposite the inlet- 25 port of one cylinder and the exhaust-port of the other, so that a relatively large opening is quickly secured.

For the purpose of balancing the lateral pressure of the steam upon the piston to prevent leakage, we form in the cylinder and diametrically opposite the inlet-port G, a chamber, G⁶, which communicates with the steam-supply passage a⁵, and is provided with a removable cap, G⁶. Within this chamber is 30 fitted a ring, g⁶, provided with a packing, g⁷, on its exterior, and adjusted and held in position by set-screws g⁸, passing through the cap G⁶, with their ends seated in recesses or sockets formed in the ring. The face of this ring 35 g⁶ is made concave to correspond to the inner surface of the cylinder, and the periphery of the piston and the area of the opening through which the steam is exposed to the surface of the piston equals the area of the inlet-port G, so that a balance of pressure is secured. The 40 ring g⁶, which merely serves as a packing or valve to prevent the escape of steam at this point, is held to its place against the piston by the pressure of the steam upon its outer 45 end. By employing the open valve, held to its work by a comparatively slight pressure, depending upon the area exposed to the action of the steam, and causing the steam to act directly upon the piston at opposite sides, a balance of pressure is secured, without materially increasing the friction upon the surface 50 of the piston, as would be the case were the inner end of the valve g⁶ closed.

The speed of the engine is varied or controlled by means of a balanced throttle-valve, K, located between the passages a³ a⁴, leading to the cylinders, and the passage a⁵, which is in communication with the steam-jackets. This valve K is preferably formed with two 60 cylindrical heads, k, united by a central spindle, k', and a tubular casing, k'', the latter provided with two series of slots or openings, k³

k⁴, corresponding with the chambered extremities of passages a³, a⁴, and a⁵. Steam from the passage a³ is admitted to the passages a³ 70 and a⁴ and the cylinders through the tubular casing k'' when the openings k³ k⁴ stand opposite the chambered extremities of said passages, and the pressure in the cylinders can be controlled by reciprocating said valve in 75 the chamber a⁵, as will be readily understood.

The speed of the engine is automatically controlled by means of a governor driven from the shaft and operating to set or adjust the valve K to admit or cut off the steam, as follows: The removable head A' of the casing A' is provided with a cross piece, L, supporting a bearing, l, concentric with the axis of the main driving shaft, and in said bearing is mounted a sleeve, l', carrying at its inner end 80 a crank, l', engaging the end of the extension J' of the crank-pin, and at its opposite or outer end provided with a yoke, l'', in the opposite extremities of which are pivoted the governor-weights L². Working freely within the sleeve 85 l' is a pin, l¹, to which is secured a cross-head, l¹, provided with rearwardly-projecting shoulders l¹, whose ends are concaved to form bearings l¹, and each governor-weight L² is provided with an arm, l², whose free end fits 90 within and engages one of said bearings l¹, so that as the weights separate or are forced apart the arms l², acting upon the shoulders l¹ of the cross-head l¹, will cause the pin l¹ to reciprocate, and at the same time oscillate 95 slightly within the sleeve l', the extent of the movement thus produced depending upon the weight of the governor and the speed at which it is rotating. The pin l¹, whose outer extremity is curved to form a center bearing, 100 projects into a socket, l³, in the end of the valve K, so that the longitudinal motion of the pin l¹ only is communicated to the valve. Between the outer end of the valve K and the inner end of a screw, M, or equivalent 105 device passing through the cap M' of the chamber a⁶, is arranged a spring, m, which operates upon the valve K in opposition to the governor weights and can be adjusted to resist the movement of the latter in any required degree of pressure to vary the action of the governor upon the throttle-valve. An opening or duct, m', is formed through the valve K to put the outer end of the chamber a⁶ in communication with the interior of the 110 casing, and thus prevent the steam which might escape or leak into the outer end of the chamber a⁶ from exerting pressure upon the end of valve K. By the opening and closing of the valve K not only is the pressure of the 115 steam in the cylinders varied and controlled, but also that in the chamber, G⁶; hence the balancing effect upon the piston remains constant.

It will be observed that the governor and valve mechanism are supported entirely within the removable head of the main casing, and can be applied and removed therewith. The cross-piece L, which is preferably cast integral

with the head A^2 , is provided with lateral flanges t^6 , forming a receptacle, t^6 , in the head A^2 and below the governor-weights. In this receptacle the condensed water and oil accumulate, and the governor-weights, passing into and through the fluid, serve to distribute it over the working surfaces. An overflow-pipe, t^6 , is fastened in the cross-piece or its flanges, with its long end projecting downward below the level of the oil, so that the water rising in the tube will be carried off and delivered into the main casing, (which latter contains a suitable overflow or relief opening,) leaving the oil in the receptacle.

Having thus described our invention, we claim—

1. In a multiple cylinder direct-acting steam-engine constructed as described, the combination, with the crank-shaft and independent pitmen applied to the crank-shaft, of the pistons connected to their respective pitman, so as to oscillate thereon, substantially as described.

2. In a direct-acting steam-engine such as described, the combination, with the crank-shaft and independent pitmen, of the oscillating pistons, each provided with a port opening into the cylinder above the piston, and the cylinders provided with inlet and exhaust ports diagonally arranged, substantially as described.

3. In a direct-acting steam-engine, and in combination with the crank-shaft and independent pitmen applied thereto, the oscillating piston attached to each of said pitmen, the jacketed cylinders provided with inlet and exhaust ports upon their interior co-operating with a port in the piston, said inlet and exhaust ports being diagonally arranged with respect to the longitudinal movement of the pistons, substantially as described.

4. In a direct-acting steam-engine, and in combination with the cylinders containing inlet and exhaust ports, as described, the separate oscillating pistons, each provided with a port for alternately putting the cylinders into communication with the inlet and exhaust ports, said pistons connected by a ball-and-socket joint to pitmen applied to the crank-pin, and devices for oscillating said pistons as they are reciprocated within the cylinders, substantially as and for the purpose specified.

5. The combination, in a direct-acting steam-engine such as described, and with the crank-shaft, pitmen, cylinders, and oscillating pistons, of a cross-head loosely mounted upon the crank-pin and engaging the pistons to cause the latter to oscillate as the crank-shaft revolves and the pistons reciprocate, substantially as described.

6. In a direct-acting steam-engine, the combination, with the crank-shaft, the pistons, and pitmen connected to said crank-shaft, of the cylinders provided with inlet and exhaust ports co-operating with a port in each piston, and a cross-head loosely mounted upon the crank and provided with cylindrical ends en-

tering sockets in the piston, substantially as described.

7. In a direct-acting steam-engine such as described, and in combination with a cylinder provided with an inlet-port, and an oscillating and reciprocating piston working therein and provided with a port co-operating with the said inlet-port to control the admission of steam to the cylinder, a chamber communicating with the steam-supply and located opposite the inlet-port for balancing the lateral pressure of the steam upon the piston, substantially as described.

8. The combination, with the cylinder and the oscillating piston reciprocating longitudinally therein, of the inlet and exhaust ports in the cylinder and the co-operating port in the piston, and the chamber opposite the inlet-port communicating with the steam-supply and opening into the cylinder and against the piston, substantially as and for the purpose set forth.

9. In combination with the reciprocating and oscillating piston provided with a port opening above the head or diaphragm, and the cylinder in which said piston operates, provided with inlet and exhaust ports, as described, the chamber located opposite the inlet-port and communicating with the steam-supply, and the annular valve or packing working in said chamber and against the piston, substantially as described.

10. In a direct-acting steam-engine, and in combination with the driving-shaft, inclosing-casing, and cylinders exhausting into said casing, the cap-plate and packing applied to the outer end of the bearing and surrounding the shaft, and the two passages or ducts, the one between the inner end of the bearing and the interior of the casing and the other extending from the outer end of the bearing to the interior of the casing, substantially as and for the purpose set forth.

11. In a direct-acting steam-engine containing radially-arranged cylinders, a central driving-shaft carrying a crank-pin, pistons reciprocating in said cylinders and each connected to the crank-pin by a separate pitman, and a cross-head hung loosely upon the crank-pin and engaging opposing pistons, the combination of a throttle-valve governing the steam-supply passages arranged in line with the driving-shaft and a governor driven from the crank and located between the throttle-valve and driving-shaft and upon a center coincident therewith, substantially as described.

12. In a direct-acting steam-engine, the combination, with the casing and the jacketed cylinders, of the removable head provided with steam-passages communicating with said jackets and the inlet-ports of the cylinder, the central chamber in said head, and the throttle-valve located in said chamber, substantially as described.

13. In a direct-acting steam-engine wherein the steam-passages communicating with the inlet-ports connect with a chamber into which

the steam is admitted under pressure, the combination of a throttle-valve located in said chamber and provided with cylindrical ends, a slotted sleeve, and a longitudinal passage 5 whereby the pressure upon opposite ends of said valve is balanced, substantially as described.

14. In a direct-acting steam-engine, the combination, with the cylinder provided with the tubular head and the inlet and exhaust ports, of the piston with its port and tubular extension bearing the packing-rings near the outer end thereof and a pitman connecting said piston with the crank-shaft, so as to permit the 15 former to oscillate about its longitudinal axis simultaneously with its reciprocation in the cylinder, as and for the purpose specified.

15. In a direct-acting steam-engine such as described, and in combination with the cylinders and independent pistons reciprocating therein and oscillating about their longitudinal axis, the elongated inlet and exhaust ports located within the cylinder in parallel planes, but at different distances from the crank-shaft, 25 and the correspondingly-shaped port in the side of the piston and opening above the latter, substantially as and for the purpose specified.

16. In combination with the detachable head applied to the main casing and provided with 30 a rotary governor, as described, the receptacle formed in said head below the governor-weights and provided with the overflow-pipe dipping below the level of the oil to carry off the water, substantially as described.

35 17. In combination with the cylinder, pis-

ton, crank-shaft, and connecting-rod of a steam-engine, the steam and balancing ports located upon opposite sides of the piston and in the plane of the rotation of the crank, whereby the lateral thrust of the crank upon the piston 40 is opposed by the steam-pressure in one of said ports, substantially as described.

18. In a steam-engine such as described, and in combination with the crank-pin thereof, the sleeve L' , supported in the cross-piece L 45 and provided with yoke l' and crank l' , governor-weights L^2 , hung on pivots in the yoke l' and provided with arms, the pin l' , supported within the sleeve L' and provided with bearings to receive the arms of the governor- 50 weights, and the throttle-valve K , having a bearing at one end to receive the pin l' , substantially as described.

19. In a direct-acting steam-engine, a central casing and jacketed cylinders, in combination with a removable head carrying throttle-valve and governor, substantially as described. 55

20. In a steam-engine such as described, wherein the pressure of steam in the inlet-port is directed against the side of the piston during a portion of its stroke, and in combination with said piston and the cylinder containing the inlet-port, a balancing-port opening against the piston, as and for the purpose set forth. 60
